OUTSIDE PIPE CUTTER

George A. Lowrey, Houston, Tex.

Application February 13, 1939, Serial No. 256,108

4 Claims. (Cl. 164—0.6)

This invention relates to an outside pipe cutter.

An object of the invention is to provide a cutting tool shaped to be telescoped over a pipe stuck in a well bore and having means for cutting of a section of the stuck pipe, by rotating the tool, and including means for withdrawing the cut off section from the well upon withdrawal of the tool.

Another object of the invention is to provide an outside cutting tool comprising a body with inwardly movable cutting means therein normally held retracted, an actuator within the body, yieldable means for holding the actuator inactive, and means engageable underneath a coupling on the pipe whereby, upon upward movement of the cutter body, and cutting means, the actuator will be held in stationary position to move the cutting means inwardly into cutting relation with the pipe whereupon the pipe will be severed upon rotation of the tool.

It is another object of the invention to provide a cutting tool of the character described wherein the cutting means and cutting actuator will return to inactive positions upon release of the upward tension on the operating string.

With the above and other objects in view the invention has particular relation to certain novel features of construction, operation and arrangement of parts, an example of which is given in this specification and illustrated in the accompanying drawing, wherein:

Figure 1 shows a vertical, sectional view of the tool telescoped over a pipe to be cut.

Figure 2 shows a cross-sectional view taken on the line 2—2 of Figure 1.

Figure 3 shows a fragmentary, vertical, sectional view showing the cutters in active, or operating position, and

Figure 4 shows a cross-sectional view taken on the line 4—4 of Figure 3.

Referring now more particularly to the drawing wherein like numerals of reference designate the same parts in each of the figures, the numerals 1, 1a designate lower and upper sections of a tubular cutter body shown connected together by threads and the upper section is attached to a tubular operating string 2 which extends to the ground surface. The lower end of the body section 1 is inwardly thickened and has the downwardly flared guide 3 whereby the tool may be guided over the upper end of the pipe 4 stuck in a well. Above the guide 3 the body has an internal, annular shoulder 5 on which an antifriction ring 6 is located which supports the helical spring 7.

The lower end of the upper section 1a forms an inside, annular shoulder 8 against which the inside anchor ring 9 abuts. The lower ends of the flexible arms 10 are secured to this anchor ring and the upper ends of these arms converge inwardly. The arms will expand upon downward movement of the tool over the pipe so as to readily pass over pipe couplings as 11 but upon upward movement of the tool the upper ends of said arms will engage underneath the coupling. Seated upon the upper end of the spring 7 there is an anchor ring 12 and between the rings 9 and 12 there is an antifriction ring 13.

Within the spring 7 and attached at its upper to the anchor ring 12 there is a sleeve-like cutter 15 actuator 14 whose lower end is outwardly thickened forming the annular shoulder 15 which normally registers with the shoulder 5. The lower end of the actuator is outwardly flared and formed with a curved bearing surface 16.

Beneath the shoulder 5 the cutter body has the inside, vertical grooves forming cutter guides 17 whose upper ends have the inwardly curved bearing surfaces 18 and whose lower ends are formed with the arcuate seats 19. Cutters 20 are located in said guides. Their lower ends are curved to conform to the shape of the seats 19 and are pivoted on the transverse pins 21. The cutters are normally held retracted, or withdrawn into the guides, as shown in Figure 1, by the flat pressure springs 22. The upper ends of the cutters are inwardly curved and bear against the curved surface 16 and terminate in the forwardly directed cutting points 23.

In operation the tool may be lowered into the well over the pipe 4 to be cut. When the desired location has been reached the tool may be pulled upwardly until the upper ends of the arms engage underneath the next collar above. Upon a further upward pull on the string 2 the body 40 of the cutter will move upwardly relative to the ring assembly 9, 12, 13 thus placing the spring 7 under compression. The actuator 14 however, will be held against upward movement. The cutters 20 will move upwardly with the body and 45 their outer curved surfaces will frictionally engage, and be forced inwardly by, the curved face 16 of the actuator thus forcing the cutters inwardly into cutting relation with the pipe 4 and upon rotation of the tool the pipe will be severed as shown in Figure 3. As the tool rotates the friction of the cutters against the lower end of the actuator will hold said actuator against rotation so as to prevent undue wear on the lower end of the actuator and on the cutters. 55

When the pipe has been cut the cut off section may be withdrawn with the tool from the well. If it is desired, at any time, to lower the tool relative to the pipe 4 it may be moved downwardly 5 thus relieving the compression on the spring 7 and the cutters 20 will be released from the pipe 4 and moved back into the guides 17 by the pressure of the springs 22. Upon such downward movement of the body the expansion of the 10 spring 7 will cause the actuator 14 to assume its original position as shown in Figure 1.

An illustration of the tool is shown in the drawing but it is obvious that mechanical changes may be made therein within the scope 15 of the appended claims.

What I claim is:

1. An outside pipe cutter adapted to cut by rotation and shaped to telescope over a pipe in a well and comprising a body, an inside shoulder 20 in the body, a yieldable member supported on said shoulder, a ring assembly supported on said yieldable member, means on the assembly arranged to be expanded by and to pass over pipe couplings upon downward movement of the body 25 and engageable with a pipe coupling to hold the assembly stationary upon upward movement of the body and to thereby place the yieldable member under compression, inwardly movable cutting means in the body, a cutter actuator depending 30 from the ring assembly and engageable with the cutting means to move the same inwardly into cutting relation with the pipe upon upward movement of the body.

2. An outside pipe cutter shaped to telescope 35 over a stuck pipe in a well and comprising a cutter body, cutters pivoted in the body, an inside shoulder in the body above the cutters, a coil spring supported by said shoulder, annular anchoring means in the body supported by the 40 spring, means attached to the anchoring means and arranged to be expanded by outside couplings on the pipe upon downward movement of the body, and engageable underneath an outside coupling on the pipe upon upward movement of the body to place said spring under compression, 45 a cutter actuator within the spring and supported thereby and having an annular lower end face engageable behind the cutters to move them inwardly upon upward movement of the body relative to the pipe.

3. An outside pipe cutter adapted to cut by rotation and shaped to telescope over a pipe stuck in a well bore and comprising a tubular body having an inside, annular shoulder, a lower ring 55 on the shoulder, a spring on said ring, an upper ring assembly in the body supported by said spring, a cutter actuator depending from said

assembly within said spring and having a lower external shoulder on which the lower ring rests, pipe engaging means supported by said upper ring assembly and expansible to pass over outside couplings on the pipe upon downward movement 5 of the body and engageable with an external shoulder on the pipe whereby upon upward movement of the body the spring will be placed under compression, inwardly movable cutting means pivoted in the body and engageable with the lower end of the actuator to move the cutters inwardly, into cutting relation with the pipe, upon upward movement of the body relative to the pipe.

4. An outside pipe cutter adapted to cut by 15 rotation and shaped to telescope over a pipe stuck in a well bore and comprising a tubular cutter body having an inside annular, lower shoulder, a lower anti-friction ring on the shoulder, a coil 20 spring on the ring, an inside annular downwardly facing upper shoulder in the body, an anchor abutting said upper shoulder, inwardly converging flexible arms whose lower ends are secured to the anchor ring and whose upper ends are free, said upper ends being expansible outwardly 25 to pass freely over outside couplings on the pipe upon downward movement of the body and to engage underneath a coupling upon upward movement of the body, an anchor ring supported on said spring, an intermediate anti-friction ring 30 between said anchor rings, a sleeve-like cutter actuator within the spring whose upper end is attached to the lower anchor ring and whose lower end is outwardly thickened forming an annular shoulder which normally registers with 35 the lower shoulder in said body, said lower end of the actuator being outwardly flared, and formed with a curved bearing surface, said body having inside vertical grooves forming cutter guides and whose upper ends have inwardly 40 curved bearing surfaces and whose lower ends are formed with arcuate seats, cutters located in said guides whose lower ends are curved to conform to the shape of said seats and are pivoted in said guides, pressure springs normally holding 45 the cutters retracted, the upper ends of the cutters being inwardly curved and bearing against the curved surface of the actuator and terminating in inwardly directed cutting points, whereby upon upward movement of the body and 50 the engagement of said arms with a coupling the coil spring will be placed under compression and the cutters will be moved to cutting relation with the pipe to sever the same upon rotation of the body.

GEORGE A. LOWREY.
